UNITED STATES PATENT OFFICE.

CHARLES R. BRADLEY, OF CHICAGO, ILLINOIS, AND SARAH C. SMITH, OF PHILADELPHIA, PENNSYLVANIA.

GARMENT.

1,285,917.

Specification of Letters Patent. Patented Nov. 26, 1918.

Application filed March 4, 1918. Serial No. 220,189.

To all whom it may concern:

Be it known that we, CHARLES R. BRADLEY and SARAH C. SMITH, citizens of the United States, respectively residing at Chicago, in the county of Cook and State of Illinois, and at Philadelphia, in the county of Philadelphia and State of Pennsylvania, have invented certain new and useful Improvements in Garments, of which the following

10 is a specification.

Our invention relates to improvements in garments.

One of the objects of our invention is to provide a useful, convenient and comfortable garment, having a large range of utility and adaptability.

Another and more specific object of our invention is to provide a one piece garment for covering the shoulders, arms and throat.

20 Other and further objects of our invention will become readily apparent to persons skilled in the art from a consideration of the following description when taken in conjunction with the accompanying drawings, 25 wherein—

Figure 1 shows the garment as it appears upon a wearer.

Fig. 2 is a modification showing that the sleeves may terminate in gloves, when desired.

Fig. 3 is a plan view of the garment when spread out.

In all the views the same reference characters are employed to indicate similar parts.

35 The garment is, preferably, a one piece structure, comprising two sleeves joined by a cape part, to cover the arms and a portion of the back of the wearer. The cape may extend down the back as far as desired, and the sleeves may terminate in mitts or gloves. This variation is especially desirable when the garment is made of a woolen knitted fabric, and particularly useful for wear by children, as a means for protecting a vulnerable portion of the torso and for the pur-

pose of retaining the gloves on the hands of the child.

The garment may also be made use of in association with a woolen scarf, so that they may be worn together in lieu of a "sweater" 50 or either garment may be independently removed and the other retained when localization of warmth is desired.

When the garment is made of water-proof material, such as oil cloth, it will be 55 highly appreciated by men who deliver ice, by carrying it on their shoulders; the water of condensation will be readily shed from the shoulder and back by the impervious covering, leaving the under garments dry 60 and warm.

There are other uses, no doubt, for the garment, which will be readily suggested from a mature consideration of its advantages.

65 In the drawing 5 represents the cape or body part which joins the sleeves 6 and 7.

The sleeves may terminate in cuffs 8 and 9, as shown in Fig. 3, or when made of knitted fabric, or Jersey cloth, gloves, as shown 70 in Fig. 2, may terminate the sleeves.

The sleeves above the cuffs may be closed by snap fasteners 10 and a similar fastening device may be used to close the garment around the neck.

75 Having described our invention, what we claim is:—

A one piece garment comprising a body part having a laterally-extending, wider back-covering cape, for covering the back 80 below the shoulders of the wearer; an oppositely disposed collar part to button around the neck of the wearer; wrist engaging cuffs terminating the body part and means to close the sleeves between the cuffs and the 85 collar.

In testimony whereof we hereunto set our hands.

CHARLES R. BRADLEY.
SARAH C. SMITH.
